UNDERFRAME

William C. Hedgecock, Wilmette, Ill., assignor
to American Steel Foundries, Chicago, Ill., a
corporation of New Jersey

Application December 13, 1933, Serial No. 702,151

32 Claims. (Cl. 105—414)

This invention pertains to car underframes and more particularly to a cast steel underframe for a four-wheel car provided with inboard roller bearing wheel and axle assemblies.

5 It is an object of this invention to provide a cast steel underframe adapted for use with a four-wheel car having wheel and axle assemblies with inboard bearings.

Another object of this invention is to provide 10 cast steel underframes wherein center sill construction is adapted as a mounting for the wheel and axle assemblies.

Still another object is to provide a car underframe having integral draft gear pocket casting and pedestals for cooperative engagement 15 with wheel and axle assemblies.

A further object is to provide a simple underframe construction wherein longitudinal and vertical strength are combined with suitable 20 mountings for draft gears and wheel and axle assemblies, without a multiplicity of members.

A yet further object is to provide a car underframe construction and spring suspension therefor which provides a four-wheel car construction 25 of easy riding qualities, is inexpensive to make and maintain, and fulfills all requirements of manufacture and service.

With these and various other objects in view, the invention may consist of certain novel features of construction and operation as will be 30 more fully described and particularly pointed out in the specification, drawings and claims appended hereto.

In the drawings, which illustrate embodiments 35 of the device and wherein like reference characters are used to designate like parts—

Figure 1 is a fragmentary top plan view of a car underframe construction embodying the invention;

40 Figure 2 is a fragmentary side elevation of the car under-frame construction illustrated in Figure 1;

Figure 3 is a fragmentary end elevation of the car underframe construction shown in Figure 1;

45 Figure 4 is a fragmentary transverse sectional elevation taken substantially in the plane as indicated by the line 4—4 of Figure 1;

Figures 5 to 11 inclusive, are enlarged fragmentary side elevations adjacent the pedestals 50 showing different forms of spring arrangements adapted for use with the car underframe construction illustrated in Figures 1 to 4 inclusive.

55 Referring first of all more particularly to the car construction illustrated in Figures 1 to 4 inclusive, the spaced pedestal sills 20 extending be-

tween the wheel and axle assemblies are provided with integrally formed suitably spaced transverse connecting members 22 and integrally formed cross members or body bolsters 24 merging into the spaced pedestal sills adjacent the pedestal jaws 26. Bracing for the sills and cross members is effected by means of the diagonally disposed brace members 28 spaced from the longitudinal center line of the underframe and integrally formed with the cross member and spaced pedestal sills.

The draft gear pocket or housing 30 is cast integral with the underframe and is provided with spaced draft sills 32 having integrally formed front and rear draft lugs 34 and 36, respectively, said sills merging into the cross members 24 at the junction of said diagonal brace members 28. The draft gear pocket is provided with the striking casting 38 and the upper connecting brackets 40 disposed adjacent thereto, adapted to be secured to the end sills 42 suitably fastened to the brackets and pockets as by means of the rivets 44. The draft gear pocket is connected to the spaced pedestal sills by means of the transversely disposed integrally formed end beam members 46 merging into the spaced pedestal sills adjacent the outer jaw of the pedestals 26, a suitable fillet 48 being disposed between the draft sills and the end beam members.

Side sills 50 are connected to the end sills as at 52 and to the spaced pedestal sills by means of suitably spaced transverse cross members 54 connected as at 56 thereto. The pedestal jaws 26 are adapted to have sliding cooperation through the wear surfaces 58 with cooperating pedestal engaging surfaces formed on the outer casing or housing 60 of the wheel and axle assembly 62. The wheel and axle assembly 62 is preferably of the inboard roller bearing type such as shown generally in Oelkers Patent No. 1,872,797, granted August 23, 1932, but may be of any type having bearings and pedestal engaging means between the opposite paired wheels.

The preferable wheel and axle assembly consists essentially of the outer stationary housing 60 and the inner rotatable axle 64 provided with the wheel 66, suitable anti-friction bearings being interposed between the inner and outer axles. In the spring suspension illustrated in Figures 1 to 4 inclusive, the housing or casing 60 is provided with the coil spring seats 67 disposed between the pedestal jaws and in vertical alignment with similar seats 68 provided on the spaced pedestal sills between said pedestal jaws, coil springs 70 being disposed between the seats 67

and 68 for resiliently supporting the underframe on the wheel and axle assembly.

In the spring suspension illustrated in Figure 5, the spaced pedestal jaws 72 are formed on the spaced pedestal sills 20 and slidably receive the housing 14 of the wheel and axle assembly 76. In this construction the housing is provided with the leaf spring seat 78 adapted to accommodate the spring band 80 of the semi-elliptic leaf spring 82, the ends of said semi-elliptic leaf spring engaging the spring seat 84 and being adapted to be received between the spaced plates 86 forming the pedestal jaws, said plates being suitably connected by means of 15 straps 88.

In the car construction illustrated in Figure 6 the spaced pedestal sills 20 are provided with the inner leaf spring seat 90 but are provided with the outer coil spring pocket 92 adapted to receive the coil spring 94 seated on the seat 96 provided in said pocket. The opposite end of the coil spring is disposed on the seat 98 supported on the outer leg 100 of the semi-elliptic leaf spring assembly 102, the inner leg 104 thereof being seated on the seat 90. The center spring band 106 of the leaf spring is received in the leaf spring seat 78 provided on the housing 14 of the wheel and axle assemblies 76. It is of course to be understood that the spring pocket 92 may be provided in place of the spring seat 90, in which case the spring seat 90 would be provided in place of the spring pocket 92, or a plurality of coil spring pockets 92 may be provided, one being disposed as shown at 92 and the other 35 in place of the spring seat 90.

In the underframe construction illustrated in Figure 7 the pedestal sills 20 are provided with the leaf spring seat 108 adapted to accommodate the upper spring band 110 of the full elliptic leaf 40 spring assembly 112, the lower spring band 114 being received in the spring seat 78 of the housing 76 of the wheel and axle assembly 74.

In the car construction illustrated in Figure 8, the pedestal sills 20 are provided with depending pedestal jaws 116 adapted to slidably receive the pedestal cooperating surfaces 118, provided on the housing 120 of the wheel and axle assembly 122. In this construction the housing is provided with the spaced coil spring seats 124 disposed on each side of the axle and shown as substantially in horizontal alignment with the cellar 126 of the housing, the pedestal jaws 116 including the spaced plates 128 and provided with the coil spring seats 130 suitably connected to 50 the plates by means of the brace members 132 as shown. These seats are shown as substantially below the top of the housing, it being understood, however, that the relative vertical position of the seats 124 and 130 may be determined by the 55 length of the spring desired. Coil springs 134 are disposed between the seats 124 and 130 for resiliently supporting the underframe on the wheel and axle assembly.

In the structures illustrated in Figures 9 to 65 11 inclusive, the pedestal sills 20 are provided with the pedestals 72 and the spaced leaf spring seats 84, all disposed between the spaced plates 86 of the pedestal. The semi-elliptic leaf springs 82 supportingly engage the spring seats 84 adjacent the ends of said springs. In the construction shown in Figure 9 the housing 76 of the wheel and axle assembly 74 is provided with the spring seat 78 adapted to receive the spring band 80 of the semi-elliptic spring. In this case the 70 pedestal sills are provided with the spaced coil 75

spring pockets 134 adapted to accommodate the coil springs 136 seated on the seats 138 in said pockets and the opposite ends thereof seating on the leaf spring assembly 82 on each side of the spring band.

In the construction shown in Figure 10, the coil springs 136 seat on the coil spring seats 138 provided in the spring pockets 134 of the pedestal sills 20, the opposite ends of the coil springs seating on each side of the spring band 80 of the leaf spring assembly 82. In this construction, however, the housing 140 of the wheel and axle assembly 142 is provided with spaced leaf spring seats 144 disposed in substantially vertical alignment with the spring seats 138 to support the leaf spring 132 in substantially vertical alignment with the contact between said coil springs and said leaf spring whereby the frictional absorption of the leaf springs is increased by compression of the leaves between the seats 144 and the 20 coil spring 136.

In the car construction illustrated in Figure 11, the housing 76 of the wheel and axle assembly 74 slidably receives the pedestals 86 and is provided with the leaf spring seat 78 adapted to receive the spring band 80 of the leaf spring assembly 82. In this case the pedestal sills are provided with a single coil spring pocket 146 having a coil spring seat 148. The coil spring 150 is seated in said pocket and on the spring cap 152 seated on the spring band 80 whereby the coil and leaf springs support the underframe in parallel relation to each other.

With the constructions shown it will be appreciated that a car underframe construction is provided adapted particularly for use with four-wheel cars providing a form of construction which is adequately strong longitudinally and vertically and provides a vehicle having easy riding qualities, and which combines its several necessary functions in a simple form whereby a minimum number of members is required.

It is to be understood that I do not wish to be limited by the exact embodiments of the device shown, which are merely by way of illustration and not limitation, as various and other forms of the device will of course be apparent to those skilled in the art without departing from the spirit of the invention or the scope of the claims.

I claim:

1. In a car construction, the combination of an inboard wheel and axle assembly having an axle provided with pedestal cooperating surfaces disposed inwardly of the wheels thereof, a cast underframe including spaced pedestal sills having pedestals including pedestal jaws cooperating with said pedestal surfaces, a cross member integrally connecting said pedestal sills substantially in alignment with said pedestals, diagonally disposed brace members connecting said pedestal sills and cross member, a draft gear housing cast integral with said cross member, said housing having draft sills each of which is in substantial alignment with the connection between said diagonal brace members and said cross member, and resilient means disposed between said jaws and interposed between said pedestal sills and said axle.

2. In a car construction, the combination of an inboard wheel and axle assembly having an axle provided with pedestal cooperating surfaces disposed inwardly of the wheels thereof, a cast underframe including spaced pedestal sills having pedestals including pedestal jaws cooperating with said pedestal surfaces, a cross member in-

provided with pedestal cooperating surfaces disposed adjacent each end thereof and inwardly of the wheels thereof, a cast underframe including spaced pedestal sills having pedestals including 5 pedestal jaws cooperating with each of said pedestal surfaces, a cross member integrally connecting said pedestal sills substantially in alignment with said pedestals, diagonally disposed brace members connecting said pedestal sills and 10 cross member, a draft gear housing cast integral with said cross member, said housing having draft sills each of which is in substantial alignment with the connection between said diagonal brace members and said cross member, resilient 15 means disposed between said jaws and interposed between said pedestal sills and said outer axle, said resilient means including a semi-elliptic spring engaging said outer axle at a plurality of points and engaging said pedestal sills at a 20 plurality of points, and a coil spring interposed between said semi-elliptic spring and said pedestal sills and engaging said semi-elliptic spring.

10. In a car construction, the combination of an inboard wheel and axle assembly having an 25 inner and an outer axle, said inner axle being normally rotatable and said outer axle being normally non-rotatable, said outer axle being provided with pedestal cooperating surfaces disposed adjacent each end thereof and inwardly 30 of the wheels thereof, a cast underframe including spaced pedestal sills having pedestals including pedestal jaws cooperating with each of said pedestal surfaces, a cross member integrally connecting said pedestal sills substantially in alignment 35 with said pedestals, diagonally disposed brace members connecting said pedestal sills and cross member, a draft gear housing cast integral with said cross member, said housing having draft sills each of which is in substantial alignment 40 with the connection between said diagonal brace members and said cross member, resilient means disposed between said jaws and interposed between said pedestal sills and said outer axle, said resilient means including a semi-elliptic 45 spring engaging said outer axle at a plurality of points and engaging said pedestal sills at a plurality of points, and spaced coil springs engaging said pedestal sills and a leaf of said semi-elliptic spring.

50 11. In a car construction, the combination of an inboard wheel and axle assembly having an inner and an outer axle, said inner axle being normally rotatable and said outer axle being normally non-rotatable, said outer axle being provided with pedestal cooperating surfaces disposed adjacent each end thereof and inwardly of the wheels thereof, a cast underframe including spaced pedestal sills having pedestals including 55 pedestal jaws cooperating with each of said pedestal surfaces, a cross member integrally connecting said pedestal sills substantially in alignment with said pedestals, diagonally disposed brace members connecting said pedestal sills and cross member, a draft gear housing cast integral 60 with said cross member, said housing having draft sills each of which is in substantial alignment with the connection between said diagonal brace members and said cross member, and resilient means disposed between said jaws and said outer axle, said resilient means including coil 65 springs disposed between the top of said outer axle and said pedestal sills.

12. In a car construction, the combination of 75 an inboard wheel and axle assembly having an

inner and an outer axle, said inner axle being normally rotatable and said outer axle being normally non-rotatable, said outer axle being provided with pedestal cooperating surfaces disposed adjacent each end thereof and inwardly of the 5 wheels thereof, a cast underframe including spaced pedestal sills having pedestals including pedestal jaws cooperating with each of said pedestal surfaces, a cross member integrally connecting said pedestal sills substantially in alignment 10 with said pedestals, diagonally disposed brace members connecting said pedestal sills and cross member, a draft gear housing cast integral with said cross member, said housing having draft sills each of which is in substantial alignment 15 with the connection between said diagonal brace members and said cross member, and resilient means disposed between said jaws and interposed between said pedestal sills and said outer axle, said resilient means including a coil spring disposed 20 between the top of said outer axle and said pedestal sills.

13. In a car underframe, the combination of spaced pedestal sills having pedestal jaws disposed in substantially opposite relation, a cross member disposed between said sills adjacent said jaws, draft members extending from said cross member, end beam members connecting said sills to said draft members intermediate the ends of said draft members, and diagonal brace members 30 connecting said sills and cross member.

14. In a car underframe, the combination of spaced pedestal sills having pedestal jaws disposed in substantially opposite relation, a cross member disposed between said sills adjacent said 35 jaws, draft members extending from said cross member, end beam members connecting said sills to said draft members intermediate the ends of said draft members, and diagonal brace members connecting said sills and cross member, said brace members being connected to said cross member in substantial alignment with said draft members.

15. In a car underframe, the combination of spaced longitudinally disposed pedestal sills having depending pedestal jaws disposed in substantially opposite relation, a cross member disposed between said sills adjacent said jaws, draft members extending from said cross member, and end beam members connecting said sills to said draft 50 members intermediate the ends of said draft members.

16. In a car construction, the combination of an inboard wheel and axle assembly having an axle provided with pedestal cooperating surfaces disposed inwardly of the wheels thereof, a car underframe supported thereon, said underframe comprising longitudinally disposed sills having pedestal jaws disposed in substantially opposite relation and cooperating with said surfaces, a cross member disposed between said sills, draft members extending from said cross member, and end beam members connecting said sills to said draft members intermediate the ends of said 60 draft members.

17. In a car construction, the combination of an inboard wheel and axle assembly having an axle provided with pedestal cooperating surfaces disposed inwardly of the wheels thereof, a car underframe supported thereon, said underframe comprising longitudinally disposed sills having pedestal jaws disposed in substantially opposite relation and cooperating with said surfaces, a cross member disposed between said sills adjacent said jaws, draft members extending from 70

said cross member, and end beam members connecting said sills to said draft members intermediate the ends of said draft members.

18. In a car construction, the combination of 5 an inboard wheel and axle assembly having an axle provided with pedestal cooperating surfaces disposed inwardly of the wheels thereof, a car underframe supported thereon, said underframe comprising longitudinally disposed sills having 10 pedestal jaws disposed in substantially opposite relation and cooperating with said surfaces, a cross member disposed between said sills, draft members extending from said cross member, end beam members connecting said sills to said draft 15 members intermediate the ends of said draft members, and diagonal brace members connecting said sills and cross member.

19. In a car construction, the combination of 20 an inboard wheel and axle assembly having an axle provided with pedestal cooperating surfaces disposed inwardly of the wheels thereof, a car underframe supported thereon, said underframe comprising longitudinally disposed sills having 25 pedestal jaws disposed in substantially opposite relation and cooperating with said surfaces, a cross member disposed between said sills, draft members extending from said cross member, end beam members connecting said sills to said draft 30 members intermediate the ends of said draft members, and diagonal brace members connecting said sills and cross member, said brace members being connected to said cross member in substantial alignment with said draft members.

20. In a car underframe, the combination of 35 spaced longitudinally disposed pedestal sills having depending pedestal jaws disposed in substantially opposite relation, a cross member disposed between said sills adjacent said jaws, draft members extending from said cross member, end beam 40 members connecting said sills to said draft members intermediate the ends of said draft members, and a spring seat disposed on each of said sills and embraced by said jaws.

21. In a car underframe, the combination of 45 spaced longitudinally disposed pedestal sills having depending pedestal jaws disposed in substantially opposite relation, a cross member disposed between said sills adjacent said jaws, draft members extending from said cross member, end beam 50 members connecting said sills to said draft members intermediate the ends of said draft members, and a leaf spring seat disposed on each of said sills and embraced by said jaws.

22. In a car underframe, the combination of 55 spaced longitudinally disposed pedestal sills having depending pedestal jaws disposed in substantially opposite relation, a cross member disposed between said sills adjacent said jaws, draft members extending from said cross member, and end 60 beam members connecting said sills to said draft members intermediate the ends of said draft members, each of said sills being formed with a spring pocket having a spring seat.

23. In a car underframe, the combination of 65 spaced longitudinally disposed pedestal sills having depending pedestal jaws disposed in substantially opposite relation, a cross member disposed between said sills adjacent said jaws, draft members extending from said cross member, end beam 70 members connecting said sills to said draft members intermediate the ends of said draft members, and a leaf spring seat on each of said sills and disposed within each of said pedestals.

24. In a car underframe, the combination of 75 spaced longitudinally disposed pedestal sills hav-

ing depending pedestal jaws disposed in substantially opposite relation, a cross member disposed between said sills adjacent said jaws, draft members extending from said cross member, end beam members connecting said sills to said draft members intermediate the ends of said draft members, a leaf spring seat on each of said sills and disposed within each of said pedestals, and a coil spring seat disposed between said leaf spring seats.

25. In a car underframe, the combination of 10 spaced longitudinally disposed pedestal sills having depending pedestal jaws disposed in substantially opposite relation, a cross member disposed between said sills adjacent said jaws, draft members extending from said cross member, end beam 15 members connecting said sills to said draft members intermediate the ends of said draft members, a leaf spring seat on each of said sills and disposed within each of said pedestals, each of said sills being provided with a spring pocket having a 20 spring seat disposed between said leaf spring seats.

26. In a car underframe, the combination of 25 spaced longitudinally disposed pedestal sills having depending pedestal jaws disposed in substantially opposite relation, a cross member disposed between said sills adjacent said jaws, draft members extending from said cross member, end beam members connecting said sills to said draft members intermediate the ends of said draft members, said pedestal jaws comprising spaced longitudinally disposed interconnected plates, and a spring seat adjacent each of said jaws disposed between 30 said plates.

27. In a car underframe, the combination of 35 spaced longitudinally disposed pedestal sills having depending pedestal jaws disposed in substantially opposite relation, a cross member disposed between said sills adjacent said jaws, draft members extending from said cross member, end beam members connecting said sills to said draft members intermediate the ends of said draft members, said pedestal jaws comprising spaced longitudinally disposed interconnected plates, and a leaf 40 spring seat adjacent each of said jaws disposed between said plates.

28. In a car underframe, the combination of 45 spaced longitudinally disposed pedestal sills having depending pedestal jaws disposed in substantially opposite relation, a cross member disposed between said sills adjacent said jaws, draft members extending from said cross member, end beam 50 members connecting said sills to said draft members intermediate the ends of said draft members, said pedestal jaws comprising spaced longitudinally disposed interconnected plates, and spring 55 seats of different character disposed adjacent said jaws and between said plates.

29. In a car underframe, the combination of 60 spaced longitudinally disposed pedestal sills having depending pedestal jaws disposed in substantially opposite relation, a cross member disposed between said sills adjacent said jaws, draft members extending from said cross member, end beam members connecting said sills to said draft members intermediate the ends of said draft members, said pedestal jaws comprising spaced longitudinally disposed interconnected plates, a leaf spring 65 seat adjacent each of said jaws disposed between said plates, and a coil spring seat between said leaf spring seats.

30. In a car underframe, the combination of 70 spaced longitudinally disposed pedestal sills having depending pedestal jaws disposed in substantially opposite relation, a cross member disposed between said sills adjacent said jaws, draft mem- 75

bers extending from said cross member, end beam members connecting said sills to said draft members intermediate the ends of said draft members, said pedestal jaws comprising spaced longitudinally disposed interconnected plates, said sills being provided with leaf and coil spring seats between said spaced plates.

31. In a car underframe, the combination of spaced longitudinally disposed pedestal sills having depending pedestal jaws disposed in substantially opposite relation, a cross member disposed between said sills adjacent said jaws, draft members extending from said cross member, end beam members connecting said sills to said draft members intermediate the ends of said draft members, said pedestal jaws comprising spaced longitudinally disposed interconnected plates, said sills being provided with a leaf spring seat depending

between said plates and a recess between said plates provided with a coil spring seat.

32. In a car underframe, the combination of spaced longitudinally disposed pedestal sills having depending pedestal jaws disposed in substantially opposite relation, a cross member disposed between said sills adjacent said jaws, draft members extending from said cross member, end beam members connecting said sills to said draft members intermediate the ends of said draft members, said pedestal jaws comprising spaced longitudinally disposed interconnected plates, said sills being provided with leaf spring seats depending between said plates and recesses between said plates and leaf spring seats provided with coil 15 spring seats. 5 10 15

WILLIAM C. HEDGCOCK.
